UNITED STATES PATENT OFFICE

RUDOLPH BECKER, OF NORTH PLAINFIELD, NEW JERSEY, ASSIGNOR TO THE SINGER
MANUFACTURING COMPANY, OF ELIZABETH, NEW JERSEY, A CORPORATION OF
NEW JERSEY

SEWING MACHINE

Application filed October 28, 1931. Serial No. 571,557.

This invention relates to sewing machines of the type having laterally vibrating stitch-forming mechanism adapted for the formation of zigzag stitches and has for one of its objects to provide improved means for vibrating the loop-taker in unison with the needle in such a manner as to maintain a fixed working relation between the loop-taker and the needle at all times.

10 Another object of this invention is to provide more room under the gooseneck of the machine so that there will be ample space for the accommodation of the work.

15 Another object of this invention is to provide an improved coupling between the loop-taker actuating shaft and the loop-taker.

20 With the above and other objects in view, as will hereinafter appear, the invention consists in the devices, combinations, and arrangements of parts hereinafter set forth and illustrated in the accompanying drawings of a preferred embodiment of the invention, from which the several features of the invention and the advantages attained there-
25 by will be readily understood by those skilled in the art.

In the accompanying drawings:

Figure 1 is a side elevation, partly in section, of the machine embodying the invention.

Figure 2 is a top plan view, partly in section, of the overhanging arm.

Figure 3 is a front end elevation of the machine.

25 Figure 4 is a rear side elevation of the head of the machine.

Figure 5 is a section taken along the line 5—5 of Figure 1.

And Figure 6 is a section taken along the line 6—6 of Figure 5.

In the embodiment of this invention selected for illustration, the machine is formed with a frame having a bed 1, an upright member or standard 2 and overhanging arm 3 terminating in the head 4.

Pivotaly mounted on a stud 5 fixed to the head 4 is an oscillatory needle-bar-carrier 6 having upper and lower bearings, 7 and 8, respectively, in which the reciprocating needle-bar 9 carrying the needle 10 is journaled.

Clamped upon the needle-bar by means of a screw 11 is the split hub of a stud 12. The stud 12 is pivotally connected to the link 13 carried by one end of the vibrating lever 14 which is fulcrumed at 15 to the overhanging arm 3. The rear end of the lever 14 is connected to the pitman 16 which is actuated by the counterbalanced crank 17 on the main driving-shaft 18 journaled in the bed 1. Through these connections the needle-bar receives its reciprocatory motion from the main-shaft.

The head of the overhanging arm is provided with bosses 19 apertured to receive the presser-bar 20, the latter carrying the presser-foot 21 and being provided with a clamp-arm 22 having an inclined upward extension 22' which receives the pressure of flat spring 23, the latter acting to lower the presser-foot upon the material when the presser-bar is released by the usual lifting lever 24.

Carried by the head of the machine is an automatic presser-foot lifter comprising a short shaft 25 extending through an aperture in the head 4 of the machine and adapted to be moved axially therein. Fixed to one end of the shaft 25 is a lever 27, actuated by a pin 34 secured to the lever 14; and fixed to the other end of the shaft 25 is a lever 26 offset so that its end 26' extends under the clamp-arm 22 which is provided with an adjustment screw 32 engaged by said end 26'.

Secured to the guide-post 28 by means of a set-screw 29 is a block 30 having a spring-pressed plunger 31 which is forced down by the rounded edge 33 of the lever end 26' when the automatic presser-foot lifter is shifted from inactive to active position. When the operator wishes to use the automatic presser-foot lifter, pressure is applied to the hub of the lever 26, this moves the lever 26, shaft 25 and lever 27 to the dotted line position shown in Figure 3, in this position the lever 27 lies directly under or in the path of the pin 34 on the lever 14, and on each reciprocation of the needle, the lever 27 is cammed in a clockwise direction thereby raising the presser-foot.

The feeding mechanism of the machine in-

cludes the usual four-motion feed-dog 35 which cooperates with the presser-foot 21 and is actuated by any suitable mechanism, preferably that disclosed in the patent to A. Grieb, No. 1,197,735, dated September 15, 1916.

Cooperating with the needle 10 is a loop-taker 36, preferably in the form of the well known rotary chain-stitch looper having the usual loop-seizing beak 37 and loop-spreading wing 38. The looper is secured to the looper-shaft 39 which is journaled in the looper-carrier block 40 slidably held between the plates 41 and 42 fixed to the bed of the machine. Secured at one end in a guideway in the looper-carrier by the screw 43 (see Fig. 5) is a needle-throat member 44 formed at its free end with a needle-aperture 45.

Secured to the end of the looper-shaft 39 is a member 46 bifurcated to form two extending prongs 47, and to the usual main-shaft 18 a similar and complementary member 48 having two extending prongs 49 is secured. Carried by the prongs 47 and 49 is a circular member 50 of bakelized fabric provided with four rectangular channels on its outer periphery which receive the prongs. It will be observed in Figure 6 that the depth of the channels is greater than the depth of the prongs. This construction constitutes a universal coupling, and also permits the looper-carrier to be moved in the direction of its length without disturbing the driving relation between the main-shaft and looper-shaft.

Fixed to the needle-bar carrier 6 by the screws 51 is a curved arm 52 enclosed in the overhanging arm 3 and standard 2. The arm 52 is enlarged at its lower end and is provided with an elongated slot 53. Fixed to the enlarged lower end of the arm 52 by means of screws 54 is a bracket 55 to which is secured by the screw 56 one end of a second arm 57, the other end of which is fixed to the looper-carrier by the screws 58. It will be observed that the arms 52, and 57 constitute, in effect, a single rigid horizontal U-shaped member having one limb pivoted on the stud 5 and the other limb fixed to the looper-carrier 40.

Fixed to the main-shaft 18 by the set-screw 59 is a pinion 59 meshing with the gear-toothed portion 60 of a barrel-cam 61 mounted to freely rotate on the short shaft 61'. The ratio of gearing between the pinion 59 and the gear 60 is as one is to two; the cam 61 rotating at one-half the speed of the main-shaft 18. The cam 61 is provided with a cam-race 62 into which a cam-follower 63 mounted on one end of the lever 64 extends. The other end of the lever 64 is fixed to the shaft 65 which is journaled in and extends through the boss 66 made integral with the base 1. Fixed to the end of the shaft 65 extending through and protruding from the boss 66 is a lever 67 having an elongated slot 68. Adjustably secured in the elongated slot 53 of the member 52 is a block 69 and a

stud-bolt 70 the end of which extends into the slot 68 of the lever 67 where it is received by the square nut 71 slidable in the slot 68. A washer 72 is provided to separate the member 52 from the lever 67. This assembly permits the side-throw of the needle-bar carrier and looper-carrier to be varied.

The cam-race 62 is so shaped as to vibrate the needle and looper laterally of the line of feed and hold them in their extreme positions while the needle is penetrating the work and presenting its loop to the loop-taker; the lateral shift being effected while the needle is out of the work.

To further support the looper-carrier so that it will move in the arc of a circle about the pivot 5, a channel 73 is provided in the side of the looper-carrier 40. The channel 73 is in the form of the arc of a circle; the radius being the distance between the center of the pivot 5 and the center of the channel. Carried by the plate 41 is a stud 74 with its end extending into the channel 73. The pin and channel together, form a supplemental support which insures the correct travel of the looper-carrier. It is not essential that the looper-carrier 40 be rigidly connected to the needle-bar carrier 6 so long as the looper-carrier 40 is mounted for movement about the axis of the needle-bar carrier supporting stud 5 as a center. It will be obvious that any other equivalent form of mechanism may be substituted for the stud and slot connection 73 and 74.

The advantage of having the needle-bar carrier and looper-carrier swingable about a common axis is that the needle and looper maintain the same position relative to each other irrespective of the position to which they are moved about their pivot. Therefore, the looper seizes the loop from exactly the same point on the needle during each stitch-forming operation. It will also be observed that a plane containing the axis of the needle and a plane passed through the beak of the looper at right angles to the looper-shaft are always parallel. This facilitates seizing and spreading of the loop, thus, increasing the speed at which the machine may be operated.

From the foregoing description considered in connection with the accompanying drawings, the construction, manner of operation and several advantages of my improved sewing machine will be clearly and fully understood. It is apparent that such a device has a wide variety of uses, and it will be understood that the form, construction and arrangement of the several elements employed may be varied. Therefore, the privilege is reserved of resorting to all such legitimate changes therein as may be fairly embodied within the spirit and scope of the appended claims.

- Having thus set forth the nature of the invention, what I claim herein is:—
1. In a sewing machine having a throat-plate, the combination of a horizontal pivot located above the throat-plate of the machine, a needle-bar carrier swingably mounted on said pivot, a movable looper-carrier, a rigid member having one of its ends fixed to said needle-bar carrier and the other end fixed to said looper-carrier, and means for vibrating said member. 5
  2. In a sewing machine the combination of a horizontal pivot, a needle-bar carrier pivoted at its upper end to said pivot, a looper-carrier, and means for concomitantly swinging said needle-bar carrier and said looper-carrier about said pivot. 10
  3. In a sewing machine the combination of feeding mechanism, a pivoted needle-bar carrier, a movable looper-carrier, a horizontal U-shaped member having one of its limbs fixed to said needle-bar carrier and the other of its limbs fixed to said looper-carrier, and means for vibrating said member laterally 25 of the line of feed. 20
  4. In a sewing machine the combination of a pivoted needle-bar carrier, a pivoted looper-carrier, a looper having operative movements about an axis in said looper-carrier, and means for swinging said needle-bar carrier about its pivot and for swinging said looper-carrier about the same pivot in a direction longitudinally of said axis. 30
  5. In a sewing machine the combination of a fixed horizontal pivot, a needle-bar carrier and a looper-carrier swingably mounted on said pivot, and means for vibrating said needle-bar carrier and said looper-carrier in a vertical plane transverse to said pivot. 35
  6. In a sewing machine the combination of a pivot, a needle-bar carrier and looper-carrier mounted to vibrate in a vertical plane about said pivot, and means for vibrating said needle-bar carrier and said looper-carrier about said pivot. 40
  7. In a sewing machine the combination of a pivot, a needle-bar carrier pivoted thereto, a reciprocating needle journaled in said needle-bar carrier, a looper-carrier pivoted to and adapted to swing about said pivot, a looper having a shaft journaled in said looper-carrier, and means for swinging said needle-bar carrier and said looper-carrier in unison about said pivot and lengthwise of the looper-shaft. 50
  8. A sewing machine having in combination, a needle-bar carrier swingable about a horizontal pivot, a looper-carrier also swingable about said pivot, a rigid member having one end fixed to said needle-bar carrier and the other end fixed to said looper-carrier, and means for vibrating said member in a vertical plane about said horizontal pivot. 60
  9. A sewing machine having in combina- 65
  - tion, a looper-shaft, a main-shaft for actuating said looper-shaft, means for moving said looper-shaft longitudinally of itself in the arc of a circle, and an extensible and universal coupling connecting said main-shaft 70 to said looper-shaft. 75
  10. A sewing machine having in combination a horizontal pivot fixed to the head of the machine, a needle-bar carrier swingable about said pivot, a rigid member having its upper end fixed to said needle-bar carrier, a looper-carrier fixed to the lower end of said rigid member, and means for vibrating said member. 80
  11. In a sewing machine, in combination, a horizontal pivot, a needle-bar carrier swingably mounted on said pivot, a reciprocating needle journaled in said needle-bar carrier, a looper-carrier movable about said pivot, a looper-shaft journaled in said looper-carrier, feeding mechanism for feeding the work transverse to said looper-shaft, a member rigidly fixed to said needle-bar carrier and said looper-carrier, and means for vibrating said member. 85
  12. In a sewing machine, in combination, a horizontal pivot fixed to the head of the machine, a needle-bar carrier swingably mounted on said pivot, a member bowed between its ends away from the line of feed and having one end fixed to said needle-bar carrier, a looper-carrier fixed to the other end of said member, and means for vibrating said member. 90
  13. In a sewing machine, in combination, a pivot, a needle-bar carrier mounted on said pivot, a looper-carrier also mounted on said pivot, a looper-shaft journaled in said looper-carrier, a main-shaft actuating said looper-shaft, feeding mechanism for feeding the work transverse to said looper-shaft and said main-shaft, and automatic means for swinging said looper-carrier and said needle-bar carrier about said pivot. 100
  14. A sewing machine having, a bed-plate, a standard and an overhanging arm, in combination with, a pivot, a needle-bar carrier swingably mounted thereon, a swingable looper-carrier, a member connected to said needle-bar carrier and said looper-carrier and enclosed in said arm and standard and disposed in part below said bed-plate, and automatic means for vibrating said member. 110
  15. In a sewing machine, in combination, a horizontal pivot located above the throat-plate of the machine, a needle-bar carrier mounted to swing on said pivot, a looper-carrier mounted to move longitudinally of itself in the arc of a circle about said pivot, a looper-shaft journaled in said looper-carrier and movable therewith, a driving shaft mounted in fixed bearings and adapted to actuate said looper-shaft, and means under control of said driving shaft for vibrating 120
  - 125
  - 130

said needle-bar carrier and said looper-carrier about said pivot.

16. In a sewing machine, in combination, a horizontal pivot, a needle-bar carrier swingably mounted on said pivot, a reciprocating needle-bar carrying a needle journaled in said needle-bar carrier, a loop-taker cooperating with said needle in the formation of stitches, and means for concomitantly jogging said needle and loop-taker in a vertical plane, said last named means including means for causing said loop-taker to move in the arc of a circle about said pivot.

10 In testimony whereof I have signed my
15 name to this specification.

RUDOLPH BECKER.
